UNITED STATES PATENT OFFICE.

WILLIAM INGLE AND WILLIAM EVA, OF EDINBURGH, SCOTLAND, ASSIGNEES TO
MERGENTHALER LINOTYPE COMPANY, A CORPORATION OF NEW YORK.

TYPE-BAR-MAKING MACHINE.

1,135,378.

Specification of Letters Patent. Patented Apr. 13, 1915.

Application filed October 12, 1914. Serial No. 866,251.

To all whom it may concern:

Be it known that we, WILLIAM INGLE and WILLIAM EVA, subjects of the King of the United Kingdom of Great Britain and Ireland, and residing, respectively, at 3 Montpelier Terrace, Edinburgh, in the county of Midlothian, Scotland, and 92 Comely Bank avenue, Edinburgh aforesaid, have invented new and useful Improvements in or Relating to Type-Bar-Making Machines, of which the following is a specification.

The present invention relates to improvements in machines of the Mergenthaler type, commonly known under the trade mark "Linotype," for making type bars or so-called slugs, and as illustrated, for example, in United States Letters Patent to O. Mergenthaler, No. 436532. In them a vertically reciprocating organ, known as the first elevator and carrying the composed line of matrices descends to hold the said line in the casting position, and the mold for the body of the slug to be cast against that line, is moved up to the latter and forced into metal-tight contact with it. Molten metal is thereupon injected into the mold. Now the descent of the said elevator and the injection of the metal are sufficiently independent of each other for that injection to take place, in spite of the descent being incomplete, in which case the metal is discharged into the adjacent operative parts of the machine and causes considerable mischief there. To prevent this, there is a so-called vise automatic stop bar so arranged between the said elevator and mold as to require displacement by a completed descent of the former, such displacement being a condition precedent to the said movement of the mold being followed by an injection of metal, all as shown and described in the above mentioned Letters Patent. A similar mischief occurs if the composed line is so deficient in matrices or spacers, that the act of thickening the latter to the maximum—an act necessary to effect the justification of the line and performed during the time that that line is held by the elevator in the so-called vise—leaves intervals between the adjacent elements of the line. One of the jaws of the vise is fixed, and the other movable away from it, but the maximum distance through which the latter can be moved is dictated by the standard length of the slugs. To prevent the last-mentioned mischief the

metal injecting pump is held out of action by a so-called pump stopping lever which can be disengaged only by the movable jaw, and by that only when the justification of the line has moved the said jaw through the distance above mentioned, see for instance United States Letters Patent No. 659865 to G. A. Bates.

Each of the above described mischief-preventing devices is returned to its normal position by respective and suitable means such as a spring. But either or both of them may stick instead of being properly returned. If either of them is not returned it will be inoperative during the next cycle of the machine and during which it ought to be operative.

The invention consists in means whereby the non-return to its normal position of either of the mischief-preventing devices above mentioned, automatically prevents the known assembler elevator from rising to its normal height.

The known assembler elevator receives the line of matrices as they are being composed, and is then raised till it is on a level with the first elevator, when it releases a so-called delivery carriage which transfers the line from the assembler elevator into the first elevator and also effects the starting of the machine, whereupon the first elevator is automatically started on its descent to the casting position. Thus, if the assembler elevator is stopped before it completes its rise, the first elevator cannot so start, or in fact the machine itself.

The just-mentioned means of the invention consist of a stop which is pushed into the path of the rising assembler elevator, so as to stop the latter before it releases the delivery carriage, which stop is moved into the said path by a complete descent of the first elevator acting through the depression of the vise automatic stop bar or the disengaging movement of the pump stopping lever.

The accompanying drawings show a preferred constructional form of the invention. In them Figure 1 is a front elevation, and Fig. 2, a side elevation from the right of Fig. 1, but omitting the assembler elevator.

1 is the assembler elevator in the position in which it is stopped by the stop 2 when the latter is pushed into the path of that elevator's rise. This stop consists of a hori-

zontal bar, mounted by means of suitable guides such as slot and stud devices 3, to slide horizontally in either direction across the face of the so-called matrix delivery channel 4. This bar may be a single one co-operating with only the front of the assembler elevator, or bifurcated as shown in Fig. 2 to co-operate with both the front and the back of it.

5 5 is the so-called vise frame wherein is slidably mounted the vertically movable first elevator 5^a, which receives the composed line from the assembler elevator 1 and presents it to the mold for the casting operation.

10 6 is the "vise automatic" stop bar freely mounted in the vise frame 5 and adapted to be engaged by the screw 6^a carried by the first elevator.

15 7 is the front end of the pump stopping lever. The figures show both these parts 6 and 7 in their normal positions, i. e., those from which they are respectively depressed by the descent of the first elevator and moved to the right by the movement of the movable jaw, and into which positions they are returned by the respective returning means. Neither the movable jaw, nor the returning means, are included in the drawing.

20 8 is a lever of the first class fulcrumed at 9 on the front of the vise frame 5, so as to work in the vertical plane and having its left-hand end pivotally connected directly or indirectly through a rod 10, to the bar 6. Its opposite end is continued past the vise frame 5 to engage with a bell crank lever 11 fulcrumed at 12 on the end of the vise frame 5. This lever has the front end of its horizontal arm maintained in contact with the right hand of the lever 8 and a cam surface 13 on its vertical arm with a horizontal rod 14, by a spring 15 pulling on the said horizontal arm from a fixed point on the vise frame 5. This rod 14 is carried in a horizontal position on the right hand of, and in the path taken by the pump stopping lever 7, by a bracket 16 fast on a vertical lever 17 fulcrumed by its bottom end and below the rod 14 at 18 on the channel 4, and having its top end loosely connected, as by a stud and slot device 19, with the stop 2. The latter and the lever 17 have suitable returning devices such as springs 20 pulling from fixed points on the said channel 4. The rod 14 is adjustable in its bracket 16 to and from the lever 7 by a screw thread and lock nut device 21, and the angle which the two arms of the lever 11 make with each other, by a device 22.

25 30 35 40 45 50 55 60 65 The invention acts if either bar 6 or the lever 7 is not returned to its normal position after the respective depression or disengagement has been effected, and, also, if neither has been effected. Thus, as the first

elevator descends on to the top of the vise frame 5, it depresses the bar 6, and the latter, through the lever 8, makes the cam surface 13 raise the rod 14 and, through the lever 17, move the stop 2 into the upward path of the assembler elevator 1, as indicated by the dotted lines in Fig. 1, thereby stopping it before it completes its rise and, consequently, preventing the first elevator starting. The stop 2 remains in its stopping position until the bar 6 is returned to its normal position. Also, as the front end of the lever 7 is moved to the right to disengage the said lever from the metal-injecting pump, it pushes the rod 14 to the right (provided, of course, that the depression of the bar 6 had not already done it), and acts on the stop 2 in the same way and through the same means as the engagement of the surface 13 with the rod 14, with the same effect upon the assembler elevator 1 and the first elevator, the stop 2 remaining in its stopping position until the front end of the lever 7 is returned to its normal position. As soon as either bar 6 or lever 7, whichever had rocked the lever 17, or both (if both are concerned in that rocking), are returned to normal position, the springs 20 return the lever 17 and the stop 2 to theirs.

Having described our invention, we declare that what we claim and desire to secure by Letters Patent is:—

1. In a typographical machine, the combination of an automatic machine-stop-device, and means whereby the abnormal operation of said device will prevent the starting of the machine.
2. In a typographical casting machine, the combination of a carrier to present the composed line to the casting mechanism, a machine stop device adapted to be moved to inactive position by the carrier, and means to prevent the presenting movement of the carrier unless said stop device is in active position.
3. In a typographical machine, the combination of a movable assembler wherein the line is composed, an automatic machine stop device, and means controlled by the machine stop device for arresting the movement of the assembler.
4. In a typographical casting machine, the combination of a pump stop movable automatically to and from its normal position, and means for preventing the starting of the machine when said device is in abnormal position.
5. In a typographical casting machine, the combination of a carrier to present the composed line to the casting mechanism, a pump stop device adapted to be moved from its normal position by the justification of the line, and means to prevent the presenting movement of the carrier unless said device is in its normal position.

6. In a typographical composing and casting machine, the combination of a movable assembler wherein the line is composed, a pump stop device, and means controlled by said device for arresting the movement of the assembler.

7. In a linotype machine, the combination of the first elevator, the "vise automatic" controlled thereby, and means whereby the abnormal operation of said "vise automatic" will prevent the starting of the machine.

8. In a linotype machine, the combination of the movable assembler, the first elevator to receive the composed line therefrom, the "vise automatic" operated by the first elevator, and means controlled by the "vise automatic" for arresting the movement of the assembler.

9. In a linotype machine, the combination of a movable assembler, the first elevator to receive the line therefrom, the "vise automatic" movable to and from normal position under the influence of the first elevator,

a movable stop device to arrest the movement of the assembler, and connections whereby the stop device will be moved to active and inactive position as the "vise automatic" is moved from and to its normal position, respectively, for the purpose described.

10. In a linotype machine, the combination of the movable assembler, a movable locking device therefor, a pump stop device movable to and from its normal position, and connections whereby the movement of the stop device from and to its normal position effects the movement of the locking device to and from its active position, respectively.

In witness whereof we have hereunto set our hands in the presence of two witnesses.

WILLIAM INGLE.
